UNITED STATES PATENT OFFICE.

CHASE TAYLOR, OF WASHINGTON, DISTRICT OF COLUMBIA.

SEMAPHORE FOR AUTOMOBILE AND LIKE TRAFFIC.

Application filed February 8, 1922. Serial No. 535,190.

To all whom it may concern:

Be it known that I, CHASE TAYLOR, a citizen of the United States, and a resident of Washington, District of Columbia, have invented an Improvement in Semaphores for Automobile and like Traffic, of which the following description, in connection with the accompanying drawings, is a specification, like characters on the drawings representing like parts.

This invention relates particularly to semaphores for automobile or other vehicular traffic, but is not limited thereto exclusively.

15 In order that the principle of the invention may be readily understood, I have disclosed a single embodiment thereof in the accompanying drawing, wherein—

Fig. 1 is a front elevation of the complete 20 semaphore showing the "Stop" signal;

Fig. 2 is a view similar to Fig. 1 of the upper portion of the semaphore, the signal having been changed as indicated;

Fig. 3 is a view of the upper portion of 25 the semaphore partly in elevation and partly in vertical section; and

Fig. 4 is a plan view of the receptacle of the semaphore.

I have chosen to represent my invention 30 in its simplest embodiment and as applied to a street semaphore for regulating or directing automobile or other vehicular traffic. It is, however, to be understood that the invention may be embodied in other types of 35 street semaphores for regulating or directing traffic and even in certain cases in other types of semaphores for directing other traffic, such, for example, as railroad traffic. My invention, however, is peculiarly 40 applicable to the regulation of street traffic as will be evident from the following description.

No less than four per cent of people are 45 color-blind. This fact is not of serious consequences in the case of railroad traffic, because engineers are very carefully examined for this defect and are not permitted to run railroad trains if so afflicted, although re-examinations show that railroad employees 50 have become color blind subsequent to their passing examination, such color blindness occurring because of abuse of coffee, alcohol and other causes. In the case of automobile or other vehicles, however, the fact is of serious 55 importance because licenses are granted to almost everyone who can run an automo-

bile, whether or not they are afflicted with color-blindness, and moreover a very considerable percentage of vehicular traffic is composed of horse drawn vehicles, for which 60 licenses are not required. I am aware that in a common type of street semaphore the four vanes which are arranged at right angles to each other are distinguished as to the "Stop" and "Go" signals, in that two 65 of said vanes placed 180 degrees apart have notched ends, whereas the other two vanes have rounded ends. Moreover, two of such vanes are painted red and two are painted green. Such a semaphore, however, is of no 70 value at night, since it is not provided with a light.

An important object of my invention is to provide a semaphore or similar signal 75 provided with a light, the appearance of which independent of the color will produce such an effect upon a person whether or not he or she be color-blind, as to cause such person to obey the signal because conscious, from an inspection of the signal, what is indicated, and without being compelled to draw up to one side of the street or let other traffic take preference and then follow in the wake thereof.

The foregoing object is accomplished in a 80 simple manner by providing a receptacle for the light with four transparencies upon the four faces, respectively, the transparencies not only being differently colored but differently shaped, so that a person afflicted 85 with color-blindness and hence not recognizing or knowing the color will nevertheless be controlled in his or her actions by the shape of the transparencies.

Referring to that single embodiment of 90 the invention herein represented, the base of the semaphore is indicated at 1 and the upright or post is indicated at 2. Upon the upper end of the member 2 is supported 95 a receptacle 3 in such a way that it may be turned from time to time by the traffic officer. This may be done by attaching to the under side of the receptacle 3 the rod 4 within the upright or post 2 and extending 100 to some suitable point where it is provided with a handle 5 protruding through a suitable slot 6, so that the signal may be turned in the usual manner. Desirably but not necessarily the receptacle 2 is relatively 105 narrow in one dimension, as is evident from a comparison of Figs. 1 and 2. Upon the two broader faces is preferably placed an 110

indicating word, such as the word "Stop", and upon the two narrower faces is placed the word "Go", or if desired this arrangement may be reversed, but obviously the 5 longer word "Stop" is more appropriately used upon the wider faces. Assuming, however, that the broader faces have the "Stop" signal, I provide in each of said broad faces an opening 7, which 10 differs markedly in shape from the openings 8 upon the narrower faces. In the construction referred to, the openings 7 have red transparencies, such as red glass, and the openings 8 have green transparencies, such 15 as green glass. The openings 7 are of relatively great breadth as compared with their height, and the openings 8 are of relatively great height as compared with their breadth. This produces such characteristically 20 different effects that any person seeing the lights through the transparencies is controlled by and responds to the shape of the transparencies, as well as by the color of the light. If such person be color-blind, 25 his or her mind responds automatically to the shape of the transparencies. Obviously, if some other shape of receptacle or container 3 be provided the shapes of the openings 7, 8 may be varied, but in all cases 30 the "Stop" and "Go" openings contrast in shape markedly with each other.

Desirably I provide shields or screens 9, one being herein shown as each upright edge of the receptacle or container 3, so 35 that the color effects through the openings 7, 8 will not become merged or blended in such a way as to confuse persons who are not color-blind, and also so that only the intended signal shall be seen.

40 My invention is not limited to the use of shields or screens, as will be obvious to those skilled in the art.

I have stated that my invention is particularly useful in the control of night traffic, 45 because of cases of color-blindness. My invention, however, is not wholly restricted to such use, since it is evident that the signalling areas 7, 8 are so characteristically different that they impress themselves upon 50 a person in the daytime if he or she be near-sighted or not near enough to the signal to determine whether the "Stop" or "Go" word is exposed to his or her view. It is evident that in such cases the relatively 55 broad area 7 will quickly catch the sight of anyone and will convey to that person a certain impression which will be different from the impression conveyed by the relatively narrow area 8. As stated, I have 60 disclosed herein but a single embodiment of the invention. In cases of railway or like traffic, it would be unnecessary to have the different shaped openings in different faces. In such cases, they might be in the 65 same face or in two faces which are back

to back or parallel. In my copending application, Serial No. 612,165, filed January 12, 1923, and which is a continuation in part of the present application, other means embodying one form of my invention is disclosed and claimed. 70

Having thus described one illustrative embodiment of my invention, I desire it to be understood that although specific terms are employed, they are used in a generic and 75 descriptive sense and not for purposes of limitation, the scope of the invention being set forth in the following claims.

Claims—

1. A semaphore or like signalling device so having a receptacle or container adapted to receive a light, said container having a plurality of pairs of opposed faces, the faces of one pair being arranged at an angle to those of the adjacent pair, each face 85 having an opening through which the light is exposed, said openings of a given pair of faces being similarly shaped and having similarly colored transparencies but contrasting in shape and in color with the openings and transparencies of the remaining faces. 90

2. A semaphore or like signalling device for vehicular traffic having a four-sided receptacle adapted to receive a light and 95 adapted to be turned, two opposite sides of the receptacle being broader than the other two sides, the broader sides having light exposing openings therein which are relatively broad as compared with their height, 100 and the narrower side having light exposing openings therein which are relatively narrow as compared with their height for the purpose set forth.

3. A semaphore or like signalling device 105 for vehicular traffic having a four-sided receptacle adapted to receive a light and adapted to be turned, two opposite sides of the receptacle being broader than the other two sides, the broader sides having light 110 exposing openings therein, which are relatively broad as compared with their height and the narrower side having light exposing openings therein which are relatively narrow as compared with their height, said 115 openings having colored transparencies differing as to the shapes of the openings.

4. A semaphore or like signalling device for vehicular traffic having a box-like member adapted to be turned and having four 120 faces each having an indicating signal thereon, two opposite faces being broader than the remaining faces and the signals thereon differing in shape from the signal upon each of the narrower faces. 125

5. A semaphore or like signalling device for vehicular traffic having a box-like member adapted to be turned and having four faces, two opposite faces being broader than the two remaining faces, said broader faces 130

- each having a traffic controlling word and also having a relatively large area constituting a traffic controlling signal or symbol and the narrower faces having a differing traffic controlling word and also having a relatively large area constituting a traffic controlling signal or symbol, said signals or symbols of the narrower faces markedly contrasting in shape with those of the broader faces.
6. A semaphore or like signalling device for traffic having means to receive a light, said semaphore having two openings for the display of light, said openings markedly contrasting in shape for the purpose set forth and means for causing said light to be displayed in a given direction from either of said openings alternately or at will.
7. A semaphore or like signalling device for traffic adapted to receive a light, said semaphore being provided with two openings through which the light is exposed, said openings having contrastingly colored transparencies and being contrastingly shaped for the purpose set forth and means for causing said light to be displayed in a given direction from either of said openings alternately or at will.

In testimony whereof, I have signed my name to this specification.

CHASE TAYLOR.
